UNITED STATES PATENT OFFICE

EARL EDWIN HARRINGTON, OF BALTIMORE, MARYLAND

HOLDER FOR CATA MENIAL BANDAGES

Application filed November 24, 1928. Serial No. 321,736.

This invention relates to holder for catamenial bandages and has for its object to provide an improved holder whereby the pad may be clamped thereto and held against lateral or longitudinal displacement by means which is novel both in construction and operation.

The present invention is directed to a structure that is an improvement on the device disclosed in my pending application for patent, Serial Number 306,220, filed September 15th, 1928.

The invention is illustrated in the accompanying drawings, wherein,—

Fig. 1 shows the bandage holder laid out flat and as viewed from the under side thereof.

Fig. 2 illustrates the same as viewed from the upper side and with a bandage in place thereon.

Fig. 3 shows a portion of the same in side view.

Fig. 4 illustrates the device also in side elevation but stretched longitudinally to show how the tapes clamp the bandage and at the same time draw the opposite side edges of the holder up.

Fig. 5 shows a slightly modified form of holder as viewed from the under side thereof.

Fig. 6 illustrates the same as viewed from the upper side and with a bandage thereon, and

Fig. 7 shows a portion of the same in side elevation.

In the drawing, the numeral 5 designates a fabric strip having a wide intermediate portion 6 and narrower tab-like opposite ends 7.

On one side of the wider intermediate portion 6, I may provide a sheet or strip of moisture-proof material such as thin rubber 8 and I provide a binding 9 secured by a row of stitches 10, and which extends preferably all the way around the fabric strip, which binding engages the longitudinal edges of the two strips 5 and 8 and thus permanently secures those strips together with the rubber strip on top of the fabric strip.

Near the rear end of one tab, I provide two perforations 11 and 12, which latter ex-

tend through both strips 8 and 5 and each perforation is spaced from the longitudinal side edge of the holder and substantially in a straight line with but at the rear of the tape-bound side edges of the tab-like end 7.

A similar pair of perforations 13 and 14 are provided at the opposite end of the holder near the base of the other tab 7, and these perforations are also located in a straight line with but at the rear of the tape-bound side edges of said latter tab.

The purpose of these four perforations will presently be explained.

The opposite side edges of the holder have longitudinal guides or tubular channels 15 and 16 formed by cross-slitting the edge-binding 9 and producing a channel-guide therethrough.

In the structure illustrated in Figs 1 to 4, inclusive, I utilize two tapes 17 and 18 which will now be explained.

The tape 17 has one end 19 secured in the edge-binding 9 at one side edge of the tab 7 and extends straight back from said edge to and passes through the perforation 11, to the upper side of the holder. This tape 17 then crosses the holder over the upper side and extends to the opposite side edge of the holder where it enters and passes through the side guide or channel 16.

After leaving the end of this channel 16, the tape then again crosses the holder and passes down through the perforation 13 to the under side of the holder and its other end 20 then extends forwardly under the edge-binding 9 of the other tab 7.

In a similar manner, the end 21 of tape 18 is secured in the edge-binding at the opposite side edge of tab 7 and extends straight back to perforation 12; then up to and across the upper side of the holder to the side guide or channel 15, then out from channel 15 and again crosses the holder to perforation 14 and its far end 22 then secured in the edge-binding 9 of the other tab.

Thus the tapes extend from the tab at one end of the holder; cross the holder to one side edge; then extend back across the holder and down through the perforations at the opposite end and finally the extreme ends of the

tapes are secured to the tab at the other end of the holder.

By reference to Figs. 1, 2 and 3 of the drawing, it will be seen that I provide a plait or cross-fold 23 in the holder from side to side and at the base of each tab, and that the ends 19, 21 and 20 and 22 of the tapes are secured to the tabs beyond these plaits or folds so that when the crossed tapes are lifted on the upper side of the holder and a pad 24 slipped thereunder the attached ends 19, 21, 20 and 22 of the tapes will be drawn backwardly but as they are permanently attached to the tabs 7, the latter will have to pucker or fold and thus the folds or plaits 23 are produced and maintained when the pad is loosely inserted under the crossed tapes at the upper side of the holder.

When, however, the pad 24 is in place under the crossed tapes and the tab-ends 7 are secured to a body-belt under slight tension, the pull of the tabs is transferred to the tapes and the latter are drawn from opposite ends which results in two advantages.

First, the tapes securely embed themselves in the pad and hold the latter against either side or lengthwise displacement on the holder, and

Second, as the tapes are pulled longitudinally, that pull is transferred to the opposite side edges of the holder at the guides or channels 15 and 16, and the result is that the two side edges of the holder are drawn up at opposite sides of the pad 24 and provide side protection.

Moreover, by securing the tape-end to the opposite side edges of the tabs, the latter are kept stretched out in a crosswise direction and prevented from puckering.

In Figs. 5, 6 and 7 of the drawing, the holder structure is precisely the same as that disclosed in Figs. 1 to 4 inclusive, and the only difference is that in this structure I employ four tapes and omit the side guides or channels, but I gain the same result. In this structure tapes 25, 26, 27 and 28 are employed.

The tape 25 passes from the under side up through perforation 11 in the holder to the upper side and then extends across the holder to the opposite side edge of the holder where it is permanently attached at 29.

Tape 26 passes up through perforation 12, and crosses the upper side of the holder to the opposite side of the latter and terminates at 30 where it is permanently secured.

Tape 27 passes up through perforation 13, then crosses the holder to the opposite side and is permanently attached at 31, and

Tape 28 passes up through perforation 14 and also crosses the holder to the opposite side edge where it is permanently attached at 32.

It will thus be seen that when the tabs 7 are drawn apart, the tapes take up the strain and embed themselves in the pad 24, and as

the strain continues the attached ends 29, 30, 31 and 32 of the tapes draw the opposite side edges of the holder up at each side of the pad.

Having described my invention, I claim,

1. A catamenial bandage-holder comprising a flexible strip on which a pad may be laid, tapes extending from near the ends of the holder and from the under to the upper side of the latter and crossing the upper side of the holder to the opposite side edges thereof,—the length of the tapes being such as to maintain a cross-fold in the holder whereby when the ends of the holder are drawn in opposite directions the tapes will be drawn taut across the upper side of the holder and pull the opposite side edges of the holder up.

2. A catamenial bandage-holder comprising a flexible strip having a cross-fold near its end, tapes having their ends attached to the under side of the holder forward of said cross-fold said tapes extending up through the holder to the upper side thereof and crossing each other on said upper side and one tape extending to one side edge of the holder while the other tape extends to the opposite side edge of the holder whereby when the strain is placed on the end of the holder beyond the attached ends of the tapes the latter will be drawn forward and stretched over the holder and the opposite side edges of the holder will be curled upwardly.

3. A catamenial bandage-holder comprising a flexible strip having a cross-fold near each end thereof and provided at opposite sides with guide means, of tapes having their ends secured to the holder between its extreme ends and said cross-folds,—said tapes extending from the under to the upper side of the holder and crossing each other at said upper side said tapes after crossing extending to and through the guide means at the sides of the holder whereby to clamp a pad on the holder and also draw the side edges of the holder upwardly.

4. A catamenial bandage-holder comprising a flexible strip having a cross-fold near each end thereof and provided at opposite sides with guide means, of tapes having one end secured to the holder strip beyond the cross-fold and extending back across the fold and then up to the upper side of the holder, said tapes then extending crosswise of the holder to and through said guide means and then again crossing the holder and passing to the under side near the opposite end thereof and the ends of said tapes extending beyond the other cross-fold and being permanently secured to the opposite end and under side of the holder beyond said second cross-fold.

In testimony whereof I affix my signature.
EARL EDWIN HARRINGTON.
